UNITED STATES PATENT OFFICE.

MARCUS C. HOPKINS, OF WASHINGTON, DISTRICT OF COLUMBIA, ASSIGNOR, BY DIRECT AND MESNE ASSIGNMENTS, TO HOPKINS CORPORATION, A CORPORATION OF DELAWARE.

LOUD-SPEAKING TELEPHONE.

Application filed May 9, 1924. Serial No. 712,012.

To all whom it may concern:

Be it known that I, MARCUS C. HOPKINS, residing at Washington, District of Columbia, have invented certain new and useful 5 Improvements in Loud-Speaking Telephones; and I do hereby declare the following to be a full, clear, and exact description of the invention, such as will enable others skilled in the art to which it appertains to 10 make and use the same.

This invention has to do with telephone receiving instruments and more particularly instruments of the loud speaking type.

The invention has for its object to produce 15 a telephone receiving instrument and particularly a loud speaking telephone instrument, characterized by increased efficiency and improved quality of reproduction.

It is a matter of common knowledge that 20 the efficiency of ordinary telephone receiving instruments is very low, and hence that the volume of sound produced by such instruments is small as compared with the electrical energy required to operate them. In 25 line with the object of obtaining increased efficiency the invention is directed toward decreasing as much as possible certain of the electrical or magnetic losses which account for the low efficiency of ordinary telephone receiving instruments. The invention contemplates a magnetic telephone structure 30 having a diaphragm pivotally supported on an annular fulcrum concentric therewith and of smaller diameter than the diaphragm; a permanent magnetic field acting 35 on the diaphragm both inside and outside the annular fulcrum so as to give the diaphragm a substantially balanced bias; and an electromagnetic field energizable in accordance with electrical signaling impulses 40 and arranged so as to actuate the diaphragm inside and outside the annular fulcrum alternately. The structural and electrical arrangement thus defined provides what 45 amounts to a push-pull actuation of the diaphragm and results, not only in markedly increased efficiency, but in materially improved quality of reproduction.

In addition to the novel feature of construction referred to above, a further feature of this invention which contributes largely to the improved quality of reproduction realized consists in providing an open 50 passage of substantial area extending from the back of the diaphragm to the open air.

Still another feature of the invention consists in the provision of permanent magnets of helical form, by which arrangement the permanent magnetic elements can be made of the desired length—thus securing the necessary magnetic potentials—but at the same time keeping the size of the structure within reasonable limits.

Other features reside in the details of construction, which can be more readily 60 brought out in the description which follows:

With reference to the accompanying drawing:

Fig. 1 is a vertical cross-section of a loud 70 speaking telephone instrument representing one of the preferred embodiments of the invention.

Fig. 2 is an elevational view corresponding to Fig. 1.

Fig. 3 is a horizontal cross-section along the lines 3—3 of Fig. 1, and

Fig. 4 is a horizontal cross-section along the line 4—4 of Fig. 1.

A pressed or spun, iron, or soft steel member 1 and an annular member 2 of the same material are assembled together and form, in combination, a channel in which is seated a ring winding 3 which is the actuating 80 winding of the device.

A ring 4 preferably of hard rubber or some other suitable non-metallic substance is supported on the winding 3 and positioned concentrically with respect thereto. The ring 4 is formed with a pointed annular 85 projection on which is supported a magnetic diaphragm 5. With the ring 4 properly positioned, a suitable filler of self-hardening substance such as beeswax, or one of the well known insulating compounds, is poured 90 into the channel. Upon hardening, this 95 filler serves to hold the winding and ring 4 in place.

The portion of the structure above the diaphragm comprises a circular plate 6 preferably of iron or soft steel, a ring 7 of the same material attached to the plate 6 by means of round head screws 8 and a throat member 9 which may be conveniently made of brass. The ring 7 is channeled at 7^a to 100 form a recess in which is seated a strip of soft rubber tubing 10. The tubing 10 bears against the diaphragm 5 in opposition to the annular pointed projection 4^a. The functions of the rubber tubing 10 are to close the 105

percussion chamber and hold the diaphragm in its proper position while—by reason of its resiliency—permitting free vibration of the diaphragm.

6 The member 1 is formed with a flange 1^a preferably corresponding in diameter with that of plate 6. Four U-shaped spacers 11 of brass or other non-magnetic material are disposed between the flange 1^a and plate 6. 10 These spacers provide support for plate 6 and are secured to both plate 6 and flange 1^a. Helix shaped, permanently magnetized bars 12 are disposed between plate 6 and flange 1^a and secured to each of these members by means of suitable screws 13. By 15 reason of the helical formation of the bars 12, a cheap grade of magnet steel may be used and the requisite length may be conveniently secured without unduly increasing 20 the overall dimensions of the structure. If high grade magnet steel is used, the helix shaped magnet bars generally may be dispensed with and straight bars extending vertically between plate 6 and flange 1^a, 25 substituted therefor.

The permanent magnetic field comprises the several permanently magnetized bars 12 in parallel, plate 6, ring 7, air-gaps *a* and *b* in parallel, diaphragm 5 air-gaps *c* and *d* in parallel, the pole pieces comprising members 1 and 2 in parallel, and the lower portion of member 1 including flange 1^a. It is evident that permanent magnetic stresses 30 are exerted on the diaphragm at points *c* and *d* respectively. The permanent stress exerted at the periphery of the diaphragm tends to displace its center portion upwardly as viewed in Fig. 1, while the stress exerted at the air-gap *d* tends to displace 35 the center portion of the diaphragm downwardly as viewed in Fig. 1.

The structure is preferably so designed and proportioned that the magnetic pull on the diaphragm at air-gaps *c* and *d* results in 40 such a balance that the center portion of the diaphragm is not materially deflected from its normal non-attracted position. In practice it is possible only to approach a condition of balance with a reasonable degree of accuracy. An absolute balance is 45 commercially out of the question and unnecessary.

In response to variable signalling currents passing through winding 3, a correspondingly variable magnetic flux is produced, the path of which comprises the channel formed by members 1 and 2, diaphragm 5 and air-gaps *c* and *d*. From a consideration of Fig. 1 it will be seen that the 50 variable magnetic polarities at the poles *c* and *d* are opposed. In other words, while one is the north pole the other is the south pole. These variable fluxes either increase 55 or decrease the magnetic pull at their respective poles depending upon whether the

polarity is such as to aid or oppose the permanent flux.

In the structure here described, only that portion of the diaphragm inside the annular fulcrum 4^a is effective for the purpose of 70 sound production. There is of course, a small amount of sound wave emission from the peripheral portion of the diaphragm, but in the present structure these sound waves are inconsequential. It is entirely 75 possible to utilize these peripherally emitted sound waves to good advantage but it is scarcely worth while in view of the increased cost of construction which would be involved. It has been found that in order 80 to realize the most satisfactory results with this device it must be so designed that the vibratory displacement of the diaphragm on either side of its normal position is substantially equal. In order to accomplish 85 this end it is necessary that the effect of the fluctuating magnetic pull at gap *c* be equal to the corresponding effect at gap *d* for the same value of impressed electrical energy. The mutually comparative proportions of 90 the respective diameters of the annular fulcrum 4^a and the means diameters of the annular air-gap areas at *c* and *d* as well as the comparative lengths of air-gaps *c* and *d* and the effective cross-sectional areas of the diaphragm inside and outside the fulcrum line are all factors 95 which must enter into consideration in designing the device with a view to accomplishing such a balanced condition as prescribed above. It is possible to approximately calculate the ideal dimensions, but in practice the calculated results can be treated only as rough approximation, for the reason 100 that there are so many factors which cannot be anticipated with certainty at the outset. The mathematics involved in making such rough calculations is of a simple character 105 which will be immediately obvious to the skilled engineer, and, therefore, requires no explanation here. In the final determination of dimensions and proportions of any new design embodying this invention 110 it will be generally found necessary to resort to cut and dry methods.

Extending from the back of the diaphragm to the open air is a passage of substantial cross-section indicated by reference character *c*. The provision of this passage 115 is an important factor in that it contributes very largely to clear and accurate reproduction. If this passage is obstructed there is a perceptible tendency for the diaphragm to become excessively damped and for this reason it is desirable to provide the device 120 with supports 14 of sufficient length to raise the flange 1^a well above the surface of the table on which it rests.

In a commercial instrument an outer casting 125 would usually be provided, in order to 130

conceal the magnet bars 12, and generally improve the appearance of the device.

The type of winding used in the structure herein described is particularly desirable in that it permits of a very large number of ampere turns at a comparatively low ohmic resistance, thereby materially reducing resistance losses and consequently increasing the efficiency of the instrument.

10 In an instrument substantially as disclosed herein, which has been constructed and successfully operated, the diaphragm is of silicon steel, 3 inches in diameter, .015 inch thick; the diameter of the annular fulcrum is $2\frac{3}{8}$ inches; the diameter of the opening at f is $1\frac{1}{2}$ inches; the diameter of the opening at g is $1\frac{1}{2}$ inches; the air-gaps are each approximately .010 inch; members 1 and 2 are each made of cold rolled steel 15 $\frac{3}{8}$ inch thick; and the winding 3 consists of 6,000 turns of No. 33 enameled copper wire.

For the purpose of preventing losses due to eddy currents, members 1 and 2 are preferably slotted through as indicated at 15 in Fig. 4.

This invention is capable of embodiment in many different forms and should not be construed as limited except as indicated by 20 the subjoined claims:

I claim:

1. In a telephone instrument, means for maintaining a continuous magnetic field, a diaphragm therein, supporting means for 35 said diaphragm, the peripheral portion of said diaphragm extending beyond said supporting means, and magnetic means operable to actuate the peripheral portion of said diaphragm.

40 2. In a telephone instrument, a diaphragm, supporting means for said diaphragm, the peripheral portion of said diaphragm extending beyond said supporting means, and magnetic means operable on said diaphragm at points thereon both inside and outside said supporting means to magnetically actuate both the peripheral portion and the center portion of said diaphragm.

50 3. In a telephone instrument, a diaphragm, supporting means comprising an annular member on which said diaphragm is supported, the peripheral portion of said diaphragm extending beyond said annular member, and actuating means adapted to act upon said diaphragm at points of application thereon both inside and outside the area thereof encompassed by said annular member.

60 4. In a telephone instrument, a diaphragm, an annular supporting member for said diaphragm, said supporting member being of smaller diameter than said diaphragm, and electromagnetic means for actuating said diaphragm, said electromag-

netic means being adapted to act magnetically upon said diaphragm at points thereon both inside and outside the area thereof encompassed by said annular supporting member.

70

5. In a telephone instrument, a diaphragm, an annular supporting member for said diaphragm, said supporting member being of smaller diameter than said diaphragm, a permanent magnetic field having parallel flux paths through the portions of said diaphragm inside and outside the area thereof encompassed by said annular supporting member respectively, and electro-magnetic means operable in response to current impressed thereon to increase the magnetic flux passing through one of said parallel paths while decreasing the magnetic flux passing through the other of said parallel paths and vice versa depending upon the direction of impressed current.

80

6. In a telephone instrument, a diaphragm, an annular supporting member for said diaphragm, said supporting member being of smaller diameter than said diaphragm, a pair of annular magnetic poles, one of said poles being adjacent the portion of said diaphragm within the area encompassed by said supporting member, the other of said poles being adjacent the portion of said diaphragm outside said area, means for oppositely and variably energizing said poles in accordance with correspondingly variable currents, whereby said diaphragm is actuated, and means for impressing a continuous magnetic potential of the same polarity on each of said poles.

90

7. In a telephone instrument, a diaphragm, an annular fulcrum on which said diaphragm is supported, the diameter of said fulcrum being substantially less than the diameter of said diaphragm, resilient means for holding said diaphragm against said fulcrum, and electro-magnetic means operable to act magnetically on said diaphragm at 100 points both inside and outside the area encompassed by said annular fulcrum.

100

8. In a telephone instrument, a diaphragm, an annular fulcrum on which said diaphragm is supported, the diameter of said 115 fulcrum being substantially less than the diameter of said diaphragm, an annular channel of magnetic material, an electro-magnet coil supported in said channel, the extremities of said channel forming magnetic poles, one of which is disposed closely adjacent the portion of said diaphragm within the area encompassed by said annular fulcrum, the other of said poles being disposed closely adjacent the portion of said diaphragm outside said area, the magnetic potentials of said poles caused by said coil being of opposite polarity, and means for impressing a continuous magnetic potential of the same polarity on each of said poles.

110

120

125

130

9. In a telephone instrument, a diaphragm, an annular supporting member for said diaphragm, said supporting member being of smaller diameter than said diaphragm, 5 means for producing a continuous magnetic field, said means having opposite magnetic poles disposed respectively on opposite sides of said diaphragm, and adjacent thereto, one of said poles being bi-furcated, the branches 10 of said bi-furcated pole being disposed adjacent said diaphragm at points within the area thereof encompassed by said supporting member and outside said area respectively, and an electro-magnet for actuating said 15 diaphragm, the branches of said bi-furcated pole forming opposite poles of said electro-magnet respectively. 10. In a telephone instrument, a dia- 20 phragm, an annular fulcrum supporting said diaphragm, said fulcrum, being of smaller diameter than said diaphragm, means for producing a continuous magnetic field, said means having opposite magnetic poles of annular form disposed respectively on oppo- 25 site sides of said diaphragm and adjacent thereto, that one of said poles which is on the opposite side of said diaphragm from said fulcrum being disposed substantially op- 30 posite said fulcrum, resilient means inter- posed between said last mentioned pole and said diaphragm and bearing against said diaphragm in opposition to said fulcrum, the other of said poles being bi-furcated, the branches 35 of said bi-furcated pole being disposed adjacent said diaphragm at points within the area thereof encompassed by said fulcrum and outside said area respectively, and an electro-magnet coil disposed between the branches of said bi-furcated pole, the extremities of the branches of said bi-furcated pole forming opposite poles of the electro- 40 magnetic field of said coil, said coil being operable upon energization to effect actuation of said diaphragm. 11. In a telephone instrument, a dia- 45 phragm, means for producing a continuous magnetic field for said diaphragm, said means comprising a permanently magnetized bar of helical form with its poles on oppo- 50 site sides of said diaphragm. 12. In a telephone instrument, a dia- phragm, means for producing a continuous magnetic field, said means including pole- 55 pieces of opposite polarity disposed on oppo- site sides of and adjacent said diaphragm, and a plurality of permanently magnetized bars of helical form. 13. The method of operating a sound pro- 60 ducing diaphragm which consists in applying actuating magnetic force to the peripheral portion thereof and to the inner portion thereof alternately. 14. The method of operating a sound pro- 65 ducing diaphragm which consists in applying a plurality of continuous magnetic at- tracting forces to the diaphragm in physical opposition and at substantially different dis- 70 tances from the center of the diaphragm, and superimposing fluctuating magnetic forces on said continuous magnetic forces in such manner that the resultant forces ap- plied to the diaphragm are altered in differ- 75 ent degrees thereby causing sound producing dis- placements of the diaphragm.

In testimony whereof I affix my signature.
MARCUS C. HOPKINS.
